F. M. S. PENNACCHINI.
HAIR CLIPPER.
APPLICATION FILED NOV. 11, 1915.

1,175,873.

Patented Mar. 14, 1916.

UNITED STATES PATENT OFFICE.

FRANCIS M. S. PENNACCHINI, OF HAVERHILL, MASSACHUSETTS.

HAIR-CLIPPER.

1,175,873.

Specification of Letters Patent. Patented Mar. 14, 1916.

Application filed November 11, 1915. Serial No. 60,958.

To all whom it may concern:

Be it known that I, FRANCIS M. S. PENNACCHINI, a subject of the King of Italy, and a resident of Haverhill, in the county of 5 Essex and State of Massachusetts, have invented certain new and useful Improvements in Hair-Clippers, of which the following is a specification.

This invention relates to hair clippers and 10 has for its object the provision of a device of this character which is adapted to regulate the length of the hair cut.

The invention consists in providing the clippers with a movable comb of varying 15 thickness which may be advanced relatively to the cutting mechanism as the latter is moved upwardly through the hair during the cutting operation.

The invention further consists in certain 20 novel features of construction and arrangement of parts which will be fully understood by reference to the description of the drawings and to the claims hereinafter given.

Of the drawings: Figure 1 represents a 25 plan of a pair of hair clippers embodying the principles of the present invention. Fig. 2 represents an elevation of the same with a portion cut in section on line 2—2 on Fig. 1. Fig. 3 represents a transverse section of the 30 same on line 3—3 on Fig. 1. Fig. 4 represents an inverted plan of the same. Fig. 5 represents a transverse section of the slide- 35 able comb on line 5—5 on Fig. 2, and Fig. 6 represents a partial view of the development of the cam cylinder drawn to an enlarged scale.

Similar characters designate like parts throughout the several figures of the drawings.

40 In the drawings, 10 is a base plate having secured thereto the casing 11 having formed integral therewith the handle 12. The base plate 10 is provided with a plurality of teeth 13 adapted to coact with the teeth 14 formed 45 in a plate 15 superimposed upon the base plate 10, said plate 15 being adapted to be reciprocated transversely of the base plate 10 by means of the actuating member 16 mounted to oscillate about the pivot pin 17 secured to the base plate 10 and casing 11 by means of the nut 18.

The actuating member 16 is provided with a handle 19 which is retained normally separated from the handle 12 by means of the 55 spring 20 surrounding the pivot pin 17 with one end secured in the casing 11, and the

opposite end bearing against the pin 21 projecting from the member 16.

When the operator grips the handles 12—19 and moves them toward each other, 60 the teeth 13—14 will coact to cut the hair as the clipper is forced through said hair.

The cutting device just described is substantially the same as the hair clippers now in general use. These clippers, however, do 65 not provide any gage or other means for regulating the cutting of the hair, which it is obvious is a desirable object to attain so that the hair may be more readily and uniformly cut. To this end the base plate 10 70 has slidably mounted thereon a frame 22 having a comb 23 removably positioned therein.

The frame 22 has two rearwardly extending arms 24 provided with teeth 25 with 75 which mesh the teeth of the gears 26 secured to a revoluble shaft 27 mounted in bearings in the ears 28 projecting from the handle 12 and the arm 29 formed integral with the casing 11. The gears 26 are driven 80 by the pinions 30 secured to and revoluble with the shaft 31 mounted in bearing in the ears 28. Between the ears 28 and mounted upon the shaft 31 is a cam cylinder 32 provided with a zigzag cam path 33 terminating 85 in a path 34 parallel to the axis of said cylinder 32. When the cylinder 32 is revolved the gears 30, 26 will be rotated, and in their rotation the gears 26 in engagement with the racks 25 will cause the frame 22 to be advanced 90 toward the teeth 14, thereby causing the comb 23 to assume a new position relatively to the cutting teeth 13—14.

The comb 23 has its front under side inclined as at 36 and when the clippers are in 95 use this inclined surface 36 bears upon the scalp so that as the comb is advanced the cutting teeth 13—14 are moved farther away from the surface of the scalp and the hair is cut longer. The gradual advancement 100 of the comb 23 is accomplished by the manipulation of the handles 12—19, causing the rotation of the cam cylinder 32. A rod 37 is mounted in a bearing in the handle 12 and in another bearing in the end of the arm 29 105 through which it extends with the end contacting with a bearing face 38 on the handle 19. A member 39 is secured to the rod 37, said member having a finger 40 extending into the cam path 33 of the cylinder 32 and 110 retained in said path by the helical spring 41 surrounding the rod 37 between the member

39 and the ear 42 projecting downwardly from the handle 12. The spring 41 is not only adapted to move the rod 37 about its axis, thereby retaining the pin 40 in the cam 5 path 33, but it also acts upon the member 39 forcing the rod 37 outwardly against the handle 19 and returning it to its normal position as shown in Fig. 1.

When the handle 19 is moved toward the 10 handle 12, the member 39 will be moved therewith, this causing the finger 40 in the cam path 33 to rotate the cylinder 32 as it moves against the inclined wall of the cam path. When the handle 19 has been 15 moved its full distance toward the handle 12 the pin 40 will enter the pocket 42 and when the gripping pressure is released from the handles 12—19 and the spring 41 forces the handle 19 outwardly to its normal position, the pin 40 will contact with the wall 43 and continue the rotation of the cylinder 32 in the same direction until said pin 40 reaches the path 34 when the pin 40 will reciprocate in a straight line without im- 20 parting further movement to the cam cylinder 32. Reverse movement of the pinion 30 is prevented by the pawl 44 engaging the teeth thereof as shown in Fig. 2. A spring 45 normally retains the pawl 44 in engage- 25 ment with said teeth until disengaged by the operator pressing down on the pad 46 to disengage the pin 40 from the cam path 33. The member 39 provided with the pad 46 is secured to the rod 37 and rocks there- 30 with so that when the rod 37 is rocked by the depression of the pad 46 the finger 47 will engage the cam surface 48 and disengage the pawl 44 from engagement with the teeth of said pinion 30. When the pawl 44 35 is disengaged in this manner the operator may manually return the comb 23, frame 22, gears 26—30, and cam cylinder 32 to their normal positions, and then by releasing contact with the pad 46 the spring 41 will re- 40 turn the pin 40 into engagement with the cam path 33 ready for another operation. 45

It is believed that the operation of the device and its many advantages will be fully understood without further description.

50 Having thus described my invention, I claim:

1. In a device of the class described, the combination of a cutting mechanism; a 55 slideable comb thereon; a revolute member for controlling the position of said comb having a peripheral cam groove; and movable means actuated by the operating means of said cutting mechanism including a pin engaging said cam groove and adapted in its 60 movement to rotate said cam.

2. In a device of the class described, the combination of a cutting mechanism; a slideable comb thereon; a revolute member for

controlling the position of said comb having a peripheral cam groove; a slideable 65 member actuated by the handles of said cutting mechanism; and a finger thereon engaging said cam groove whereby said cam will be rotated during the movement of said slideable member. 70

3. In a device of the class described, the combination of a cutting mechanism; a slideable comb thereon; a revolute member for controlling the position of said comb having a peripheral cam groove; a slideable 75 member actuated by the handles of said cutting mechanism; a finger thereon engaging said cam groove; and means for disengaging said finger from said cam groove.

4. In a device of the class described, the combination of a cutting mechanism; a slideable comb thereon; a revolute cam member for controlling the position of said comb having a zigzag cam path; and means actuated by the operating means of said cutting mechanism for engaging said cam path and revolving said cam. 80

5. In a device of the class described, the combination of a cutting mechanism; a comb slideable thereon and provided with a plurality of rack teeth; gearing meshing with said rack teeth; a revolute cylinder for actuating said gearing having a peripheral cam groove; and means engaging said cam groove and controlled by the movement of said cutting mechanism for actuating said cam cylinder. 90

6. In a device of the class described, the combination of a cutting mechanism; a comb slideable thereon and provided with a plurality of rack teeth; gearing meshing with said rack teeth; a revolute cam cylinder for actuating said gearing; means controlled by the movement of said cutting mechanism for actuating said cam cylinder; a device for normally preventing reverse movement of said gearing; and means for operating said device to permit the reverse movement of said gearing and the return of said comb to its normal position. 100

7. In a device of the class described, the combination of a cutting mechanism; a comb slideable thereon having variable thicknesses; a revolute member having a peripheral cam groove; means actuated by said cutting mechanism for rotating said cam member; and mechanism interposed between said cam member and said comb whereby said comb is advanced relatively to said cutting mechanism, said comb operating mechanism including a pin engaging the groove of said cam member. 110

Signed by me at 4 Post Office Sq., Boston, Mass., this 8th day of November, 1915.

FRANCIS M. S. PENNACCHINI.
